UNITED STATES PATENT OFFICE.

LOUIS DE F. MUNGER, OF SPRINGFIELD, MASSACHUSETTS.

PISTON-GROOVE TOOL.

1,351,057.

Specification of Letters Patent. Patented Aug. 31, 1920.

Application filed November 14, 1917. Serial No. 201,901.

To all whom it may concern:

Be it known that I, LOUIS DE F. MUNGER, a citizen of the United States, residing in the city of Springfield, in the State of Massachusetts, have invented certain new and useful Improvements in Piston-Groove Tools, of which the following is a specification, reference being had to the accompanying drawing, forming a part hereof.

10 It is well understood that in the use of piston-rings with the grooved pistons of gasoline engines the first or topmost groove of the piston, that is, the groove nearest the head of the piston, becomes worn with use so that the ring fits loosely therein, the lower or farther side of the groove being worn off on a slight bevel. It is usual for the repair man to replace the ring in such a groove with a ring slightly oversize, which 15 does not fit readily in the groove. In a first-class repair shop the piston, in such a case, is taken out and put into a lathe, and the groove is turned out true. This operation takes considerable time and in other shops 20 the ring is rubbed with the hand on emery paper laid on the bench, until it is reduced to the desired thickness so that it will fit closely in the groove, which is not true. This operation of rubbing down the ring, 25 however, invariably rounds off the edge of the ring so that the ring in use slips over the film of oil on the cylinder wall, instead of scraping it as it should do, and the result is that there is practically no gain from 30 the insertion of the new piston-ring. The object of this invention is to provide a tool whereby the groove can be trued up in a very few minutes, without requiring the piston to be removed and placed in a lathe and 35 with unskilled labor. The tool comprises a yoke-shaped body or carrier, adapted to fit into the groove and provided with a suitable handle, and a scraper or cutter secured to the carrier and readily adjustable to vary 40 the cut. The invention will be more fully explained hereinafter with reference to the accompanying drawing in which it is illustrated, and in which,—

Figure 1 is a view showing the tool in 45 position in the groove of a piston, the tool being shown in section.

Fig. 2 is an end view of a piston, partly broken out, with the tool in position in the groove.

50 Figs. 3 and 4 are detail views.

The body or carrier *a* of the tool may be made as a casting, with its inner face *a'* preferably curved on a radius corresponding to that of the bottom of the groove of the piston in which it is to be used. Each arm of the carrier is preferably brought to a sharp edge, as at *a''*, so that the tool may be used to scrape out the carbon or carbonized oil from the piston-groove and each end may also be split, as at *a'''*, and provided with a tapered screw *a⁴*, so that each end of the carrier may be made to fit properly within the groove. Each arm is also provided with a hook or shoulder, at *a⁵*, so that it may be engaged by a wire passed around the piston for the purpose of holding the tool in the groove. The tool is provided with a suitable handle. For convenience of use under different conditions this handle *b* may be detachable from the body and provided with a threaded stud *b'* to enter a correspondingly threaded hole in the body *a*, such hole being either axial, as indicated at *a⁶*, or transverse, as indicated at *a⁷*, so that the handle may be placed in the same plane with the body or at right angles thereto.

The cutter or scraper *c*, formed with a proper cutting edge, as at *c'*, is preferably placed in a recess *a⁸*, formed therefor in the body, and may be secured in place by a screw *c²*. It may be adjusted by a tapered pin *c³* in a threaded hole provided therefor in the body *a*.

In the use of the tool, the piston having 90 been withdrawn sufficiently from the cylinder to expose the groove and the old ring having been removed, the tool is applied to the groove and held in place by a wire engaged with the two arms thereof. It is then oscillated at different points of the circumference so as to remove the carbonized oil from the groove. Then the cutter is adjusted by the screw-threaded pin *c³*, so that as the tool is revolved about the piston the cutter shall take off a thin shaving from the beveled side of the groove, the operation being repeated until the groove has been trued up on one or both sides as may be necessary, and until the groove is of such width as to receive with a proper floating fit the oversize ring which has been provided. The fit of the ring in the groove can be tested readily by rolling the ring in the groove throughout its circumference, the tool being applied again as may be necessary to fur- 100 105 110

ther widen the groove. In this manner the groove can be trued up very quickly and by unskilled labor but with absolute accuracy.

It will be understood that various changes in details of construction can be made to suit different conditions of use or the convenience of the manufacturer or user.

I claim as my invention:

1. Apparatus for cutting grooves in the periphery of circular stock comprising a support adapted to encircle the stock, a grooving tool projecting inwardly from the support, and a plurality of guides projecting inwardly from the support in spaced relationship therearound, the guides being adapted to extend into an annular slot in the stock and having lateral bearing surfaces adapted to position the apparatus axially of the stock.

2. Apparatus for cutting grooves in the periphery of circular stock comprising a support adapted to encircle the stock, a grooving tool projecting inwardly from the support, and a plurality of guides, adjustable to fit slots of different widths projecting inwardly from the support in spaced relationship therearound, the guides being adapted to extend into an annular slot in the stock and having lateral bearing surfaces adapted to position the apparatus axially of the stock.

3. Apparatus for cutting grooves in the periphery of circular stock comprising a support adapted to encircle the stock, a grooving tool projecting inwardly from the support, and a plurality of guides, divided so as to be adjusted in width to fit slots of different widths, projecting inwardly from the support in spaced relationship therearound, the guides being adapted to extend into an annular slot in the stock and having lateral bearing surfaces adapted to position the apparatus axially of the stock.

4. Apparatus according to claim 1 further characterized in that said guides are arranged to extend into the same groove as the cutting tool.

5. A tool for truing piston-ring grooves, comprising a yoke-shaped carrier having its ends formed to fit freely in the groove and provided with a handle, and a cutter carried by the carrier with its cutting edge parallel with the side wall of the groove.

6. A tool for truing piston-ring grooves, comprising a yoke-shaped carrier having its

ends formed to fit freely in the groove and provided with a handle, a cutter carried in the carrier with its cutting edge parallel with the side wall of the groove, and means to adjust the cutter toward and away from the side wall of the groove.

7. A tool for truing piston-ring grooves, comprising a yoke-shaped carrier having its ends split and provided each with a tapered screw to make them fit in the groove of the piston and provided with a handle, and having a recess in one side thereof, and a cutter secured in said recess to act upon the side of the groove.

8. A tool for truing piston-ring grooves, comprising a yoke-shaped carrier adapted to fit in the groove of the piston and provided with a suitable handle, and a cutter carried by the carrier, the ends of the yoke being formed with sharp edges to scrape out the groove.

9. A tool for truing piston-ring grooves, comprising a yoke-shaped carrier adapted to fit in the groove of the piston and provided with a suitable handle, and a cutter carried by the carrier, the ends of the yoke being split and provided with expanding screws to make the ends fit properly in the groove.

10. Apparatus for cutting grooves in the periphery of circular stock comprising a support adapted to encircle the stock, a grooving tool projecting inwardly from the support, and a guide adjustable to fit slots of different widths, projecting inwardly from the support, the guide being adapted to extend into an annular slot in the stock, and having lateral bearing surfaces adapted to position the apparatus axially of the stock.

11. Apparatus for cutting grooves in the periphery of circular stock comprising a support adapted to encircle the stock, a grooving tool projecting inwardly from the support, and a guide divided so as to be adjustable in width to fit slots of different widths, projecting inwardly from the support, the guide being adapted to extend into an annular slot in the stock and having lateral bearing surfaces adapted to position the apparatus axially of the stock.

This specification signed this 9th day of November, 1917.

LOUIS DE F. MUNGER.
